DESIGN.

H. HUNT.

CARPET.

No. 17,201.

Patented Mar. 22, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,201, dated March 22, 1867.

Application filed February 18, 1867. Serial No. 228,126. Term of patent 3½ years.

To all whom it may concern:

Be it known that I, HENRY HUNT, a subject of the Queen of Great Britain, residing in Greenville, in the State of New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The main features of my design consist in the rose-like flower forms and conventional leaves, irregularly distributed and arranged, as shown in the photograph. Small geometrical or ornamental figures of various forms scattered in the spaces between the larger figures form an inconspicuous ground.

What I claim as new, and desire to secure by Letters Patent, is—

The design for carpets, consisting of the design substantially as shown and described.

HENRY HUNT.
